UNITED STATES PATENT OFFICE

PAUL MÜLLER, OF SOLINGEN, GERMANY

PROTECTIVE HOLDER

Application filed August 8, 1927, Serial No. 211,594, and in Germany March 26, 1927.

The invention concerns a protective holder for hollow ground permanent blades with thick backs, for safety razors, as generally known.

5 Hitherto such blades have been kept without protection in the slots of the cabinet or outfit box and were therefore readily liable to damage.

As most shavers employ seven permanent 10 blades which in order to facilitate the use of the blades in rotation for the daily shave, are stamped on the backs, with the day of the week, the invention aims to provide a protective holder which securely protects the 15 fine blade edges from damage in the slots of the box and further enables the name of the day to be read without removing the blades from the holder.

This problem is completely solved by the 20 new protective holder.

A constructional example of the subject of the invention is shown in the accompanying drawing, wherein:

Fig. 1 is a side elevation of the holder with 25 the blade,

Fig. 2 a front elevation with the blade,

Fig. 3 a plan with blade removed, and

Fig. 4 a view of the box with seven protective holders.

30 The protective holder has the form of a U-shaped clamp 1. The limbs 2 grip the blades on both sides and extend beyond the cutting edge 3 thereof and protect the latter on all sides safely from any damage, projections 35 for example being formed on the holder to grip the blade.

The day of the week may be observed 40 through the window-like opening 4 in the back of the clamping lever without removing the blade.

I claim:

1. An assembly comprising a hollow ground single edged razor blade having a thick back, and a holder consisting of a U-shaped clamp the limbs of which are provided with edges on their opposing sides bearing against opposing sides of the blade, spacing the free ends of the said limbs apart and clamping the blade in place, said limbs 50 being of greater width than the razor blade

so that their free edges extend beyond the cutting edge of the blade and said limbs having notches in their ends exposing the ends of the blade and facilitating gripping of the blade.

2. An assembly as claimed in claim 1, in which the blade has a date word on its back and the holder has an opening in the back portion thereof intermediate and connecting the limbs and through which opening said word of the blade is exposed.

In testimony whereof I have hereunto set my hand this 20th day of July, A. D. 1927.

PAUL MÜLLER.
